BY

Bradford Webster ATTORNEY

UNITED STATES PATENT OFFICE.

JOSEPH F. HOLLYWOOD, OF BROOKLYN, NEW YORK.

DESIGN FOR A CANDY TABLET OR SIMILAR ARTICLE.

53,657.

Specification for Design.

Patented July 29, 1919.

Application filed March 22, 1919. Serial No. 284,505. Term of patent 14 years.

To all whom it may concern:

Be it known that I, JOSEPH F. HOLLYWOOD, a citizen of the United States, residing at Brooklyn, in the county of Kings and State of New York, have invented a new, original, and ornamental Design for a Candy Tablet or Similar Article, of which the following is a specification, reference being had to the accompanying drawing, forming part hereof.

In the drawing: Figure 1 is a plan view; Fig. 2 is a side elevation; and Fig. 3 is a vertical cross section.

I claim:

The ornamental design for a candy tablet or similar article, substantially as shown.

JOSEPH F. HOLLYWOOD.

Witnesses:

P. L. REILLY,
H. G. THOMPSON.
